United States Patent Office

Des. 183,295
Patented July 29, 1958

183,295

COMBINED CLOCK AND LOUD SPEAKER UNIT

Dana L. Vickery, Gardner, Mass., assignor to Simplex
Time Recorder Co., Gardner, Mass., a corporation of
Massachusetts

Application April 19, 1957, Serial No. 45,799

Term of patent 14 years

(Cl. D42—7)

FIG.2

FIG.3

Fig. 1 is a front perspective view of a combined clock and loud speaker unit, showing the new design; Fig. 2 is a top plan view thereof; and

Fig. 3 is a reduced side elevational view thereof looking from the right of Fig. 1.

I claim:

The ornamental design for a combined clock and loud speaker unit, as shown.
